CLAIM

The ornamental design for a computer host as shown and described.

DESCRIPTION

FIG. 1 is a perspective view of a computer host showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the portion, labeled '9' in FIG. 1;

FIG. 10 is an enlarged view of the portion, labeled '10' in FIG. 2;

FIG. 11 is an enlarged view of the portion, labeled '11' in FIG. 6; and,

FIG. 12 is a perspective view thereof, showing the computer host of FIGS. 1–8 in a state of use.

The dashed broken lines, illustrating a set of headphones in FIG. 9, represent environment and form no part of the claimed design. All other dashed broken lines illustrate portions of the computer host that form no part of the claimed design. The long-dash short-dash broken lines represent the extents of the detail views and form no part thereof. The oblique line shading shown in the drawings indicates a transparent or translucent surface.
